UNITED STATES PATENT OFFICE.

HENRY WILLIAM BUZZARD, OF BELLINGHAM, WASHINGTON.

CHOKER HOOK.

Application filed August 14, 1923. Serial No. 657,393.

To all whom it may concern:

Be it known that I, HENRY W. BUZZARD, a citizen of the United States, and resident of Bellingham, in the county of Whatcom and State of Washington, have invented 5 certain new and useful Improvements in Choker Hooks, of which the following is a specification.

This invention relates generally to hooks, 10 more particularly to hooks of the type used in lumbering operations and known in the trade as choker hooks, and it consists in the combinations, construction and arrangements herein described and claimed.

15 An object of my invention is to provide an improvement over the hook disclosed in Patent #1,183,059 issued May 6, 1916, to John O. Balch, in which a closure for the bill of the hook was controlled by a latching 20 pin slidably disposed in a pocket in the body of the hook, being urged outwardly by a spring interposed between the end of the latch pin and the bottom of the pocket, and being guided in its movement and retained 25 in the pocket by a screw fast in the body of the hook and received in a slot in the latching pin. It has been found in actual practice, that the closure controlling arrangement disclosed in the aforesaid patent 30 is not satisfactory nor effective for the purpose intended principally because the latching pin becomes rusted and the pocket clogged with dirt so that the pin will not spring back into extended or shot out position after it has been pressed into the pocket 35 to permit the moving of the closure to open position. Moreover, the guide screw of the device of the aforesaid patent becomes rusted in service so that it cannot be removed 40 with a screw driver, thereby necessitating the removal of the hooks to a repair shop in order that they may be again placed in condition for proper use. Obviously, this condition is very unsatisfactory and occasions 45 undue delay and expense as the hooks are ordinarily used at points remote from repair shops.

It is therefore an object of my invention 50 to provide a hook of the character described in which a novel latch mechanism for controlling the bill closing member is comprised, whereby the latching arrangement may be disassembled in the field with the use of tools ordinarily available to permit of the repair thereof or the replacement of any worn or broken part.

Other objects and advantages will be apparent from the following description, and the novel features of the invention will be particularly outlined in the appended 60 claims.

My invention is illustrated in the accompanying drawings forming a part of this application in which—

Figure 1 is a perspective view, showing 65 the improved hook operatively applied, and

Figure 2 is a vertical section through the hook, illustrating to advantage the rack teeth comprised therein.

As in the hook disclosed in the aforesaid 70 patent, a practical embodiment of my invention comprises a body 1 formed to provide a bill 2 at one end and having an eye 3 at its other end. A closure member 4 is pivotally attached at 5 to the body 1 in such 75 manner that the flange 6 formed integrally with the closure member 4 along one edge of the latter is disposed between the bill 2 and the body proper, when the closure is in the position illustrated in the drawing with 80 respect to the bill 2.

The upper edge or end of the bill 2 and the flange 6 are cooperatively curved to permit of the rotation of the closure 4 about the axis of the pivot 5 while the flange 6 is 85 in contact with the end of the bill 2.

The parts described so far are ordinary in construction and form no part of my invention except in so far as they cooperate with the parts which will now be described. 90

A bore 7 is formed through the body 1 in position to substantially register with a notch 8 in the edge of the closure remote from that provided with the flange 6 when the closure is in the position in which illustrated in the drawing. The bore 7 is enlarged diametrically or counterbored intermediate of its length as indicated at 9, thereby defining an annular shoulder 10 in the bore. The enlarged portion 9 of the bore 95 opens through the back side of the body 1 and is threaded at 11 for an appreciable distance from its outer end for engagement with a threaded plug 12.

A latching pin 13 is adapted to slide in 105 the bore 7 and has a head or flange 14 at one end adapted to slide in the diametrically enlarged portion 9 of the bore. The latching pin 13 is of sufficient length to project beyond the front side of the body 1 when the head 14 abuts the shoulder 10, whereby the closure 4 may be positioned so that the pro-

jecting portion of the latch pin will extend into the notch 8 and thus lock the closure 4 in position to close the opening between the bill 2 and the body 1, as illustrated in the 5 drawing. The plug 12 is provided with an axial socket 15 in its inner end in which is seated an expansion spring 16 having one end arranged to react against the head 14 and to thus urge the locking pin 13 to its 10 extended position. The plug 12 is of such length as to terminate at a sufficient distance from the shoulder 10 to permit of the latching pin 13 being pressed into retracted position against the action of the spring 16 so 15 that the end of the pin will be substantially flush with the front side of the body 1, whereupon the closure 4 may be rotated from the position in which illustrated in the drawing to permit of a link 17 being 20 moved between the bill 2 and the body 1 into engagement with the hook. With this arrangement described, the outer end of the plug 12 is substantially flush with the back side of the body 1 and a screw driver slot 18 25 is provided in the outer end of the plug to permit of the latter being conveniently removed or applied at will.

From the foregoing description of the various parts of the device, the operation 30 thereof will be readily apparent. In service, the link 19 of a chain will be passed through the eye 3 to attach the body 1 to the chain. The link 17 may then be placed in engagement with the hook in the manner described 35 when the closure 4 has been rotated from the position in which illustrated until the flange 6 is no longer interposed between the bill 2 and the body 1. It will be understood that the latching pin 13 must first be pressed 40 from the position in which illustrated into retracted position to permit of the rotation of the closure member 4. When the latter has been rotated to open position, the latching pin 13 will be urged outwardly by the 45 spring 16 against the under side of the closure 4, thereby holding the latter in open position until the weight 17 has been placed in engagement with the hook. In the event that rust should form on the pin 13 or on the 50 spring 16 so that these parts do not function properly, it is only necessary to remove the plug 12 to permit of inspection of the spring 16 and the pin 13 as well as of the repair or replacement of either or both of 55 these parts. The plug 12 is made of brass or like non-corrosive material and in consequence may be removed at will. It will thus be manifest that the latching arrangement comprised in the improved hooks embodying 60 my invention is thoroughly effective for the purposes intended, and obviates the necessity of removing the hooks to a repair shop by avoiding the objectionable features of the hooks provided prior to my invention.

65 Obviously my invention is susceptible of

embodiments varying in details from that illustrated and described herein and I therefore consider as my own all modifications and adaptations of the form of the device shown which properly fall within the scope 70 of the invention as disclosed in the foregoing and as outlined in the appended claims.

Having thus described my invention, what 75 I claim is:—

1. A hook comprising a body provided with a bill and a closure movably supported on the body, said body having a bore opening through the side thereof adjacent to the closure and a counter-bore opening 80 through the opposite side of the body, a locking pin slidably disposed in said bore and having an enlarged portion disposed in said counterbore, said pin being of sufficient length to project beyond the end of the bore into engagement with the closure when in an extended position, and means 85 for preventing the displacement of said pin from said bore.

2. In a hook, a body having a bore extending transversely of the longitudinal axis thereof and opening through the front side thereof, said bore being merged into a counter-bore opening through the back side of the body, and a spring pressed locking 90 pin slidable in the bore and having a head portion disposed within the counter-bore, 95 for the purpose described.

3. In a hook, a body having a bore extending transversely of the longitudinal axis thereof and opening through the front side thereof, said bore being merged into a counter-bore opening through the back side of the body, a latching pin slidable in the bore and having a head portion slidably 100 received in the counter-bore, said pin being of a length to project beyond the front side of the body when in an extended position, and means actuated to urge the latching pin 105 toward its extended position.

4. In a hook, a body portion having a bore extending transversely of the longitudinal axis thereof and opening through the front side thereof, said bore being merged into a counter-bore opening through the back side of the body, a latching pin 115 slidably disposed in the bore and having a head portion slidably received within the counter-bore, a spring disposed within the counter-bore and arranged to react against the head of the latching pin to urge the latter to its extended position, and means for preventing the displacement of the spring 120 relatively to the head and for limiting the movement of the latching pin toward the outer end of the counter-bore.

5. In a hook provided with a movable closure member, a body supporting the closure member and provided with a bore extending transversely of the longitudinal 125

axis thereof and opening through the side of the body contiguous to the closure, said bore being merged into a counterbore opening through the opposite side of the body, 5 a latching pin slidably disposed in the bore and having a head portion received within the counter-bore, said latching pin being of a length to project when in an extended position beyond the end of the bore into 10 engagement with the closure, a plug threadedly engaging the counter-bore, and an expansion spring interposed between the plug and the head of the latching pin and reacting against the latter to yieldingly resist 15 movement thereof from an extended position.

6. In a hook provided with a movable closure member, a body supporting the closure member and provided with a bore extending transversely of the longitudinal 20

axis thereof and opening through the side of the body contiguous to the closure, said bore being merged into a counterbore opening through the opposite side of the body, a latching pin slidably disposed in the bore 25 and having a head portion received within the counter-bore, said latching pin being of a length to project when in an extended position beyond the end of the bore into engagement with the closure, a plug made 30 of a non-corrosive material and threadedly engaging the counter-bore, said plug having a socket formed in the inner end thereof, and an expansion spring seated within the socket and having one end thereof reacting 35 against the head of the latching pin to continuously urge the latter toward an extended position.

HENRY WILLIAM BUZZARD.
